SOLVENT DEWAXING

Roy T. Edwards, Hollis, and Robert B. Killingsworth, Douglaston, N. Y., assignors to Socony-Vacuum Oil Company, Incorporated, a corporation of New York

No Drawing. Application November 22, 1947,
Serial No. 787,622

6 Claims. (Cl. 196—18)

1

This invention relates to a method for separating waxy oils into dissimilar constituents of wax and oil. More particularly, the present invention is concerned with an improvement for separating waxy constituents from wax-bearing petroleum oils with the aid of a selective solvent.

It is well known in the art that waxy constituents can be separated from mineral oils by various methods, all of which have in common the feature of cooling the wax-containing oil to relatively low temperatures to solidify the waxy constituents and thereafter filtering, centrifuging, or otherwise physically separating the wax from the oil-wax slurry. It is also known in the art that the separation of the wax from wax-bearing oils can be facilitated and accelerated by utilizing various diluent materials. Those methods in which the diluent used is one tending to exert a preferential solvent action for oil over waxy material at low temperatures are commonly known as solvent dewaxing methods. One widely used version of this method makes use of a mixture of an oil solvent such as benzol or toluol and a wax anti-solvent such as a ketone, for example, acetone or methyl-ethyl ketone. Other selective solvents which have been used commercially for facilitating the separation of wax and oil include light naphthas, propane, pentane, hexane, and the like, as well as various acetates, alcohols, and chlorinated hydrocarbons. The chlorinated solvents, although well known for their selectivity in separating wax from oil, have not been widely accepted by the refining industry because of high cost and relative instability. The latter undesirable property leads to the formation of hydrochloric acid which, in turn, gives rise to a problem of corrosion.

A dewaxing process wherein any of the aforementioned solvents are employed usually requires a temperature of the order of 0° F. or lower to obtain an efficient separation of waxy constituents from the oil. Other difficulties in the processes heretofore employed include changes in the ratio of the constituents of the solvent mixture when the dewaxing operation is carried out in two or more stages.

In accordance with the present invention, there has now been discovered a solvent which may be employed in separating waxy constituents from wax-bearing oils without necessitating refrigeration of the solvent-waxy oil mixture. It has been found that dewaxing operations can be effectively carried out at substantially ambient temperature to provide an excellent separation between wax and oil. The time and expense involved in cool-

2

ing the solvent-waxy oil mixture, which heretofore has been a necessary procedural step in dewaxing operations, is hence eliminated by practice of the present invention.

It has been found that fluorinated aromatic hydrocarbons boiling within the approximate range of 150° F. to 450° F. have an unusually high solvent power for oil with a comparatively low solvent action for wax. Various fluorinated aliphatic hydrocarbons, such as dichlorodifluoromethane and the like, have this property to a limited extent, but they do not accomplish the desirable results obtained with the use of fluorinated aromatic hydrocarbons boiling in the above defined range and, being extremely volatile, they are not adaptable for use at ambient temperature.

One of the major factors influencing the suitability and adaptability of a material for use as a dewaxing or deoiling solvent is its relative solubility for the waxy constituents and for the oily constituents. The ideal solvent is one which will show a relatively low solubility for the waxy constituents, will exhibit a relatively high solubility for the oily fractions, and will also remain completely miscible with the oily constituents at the temperatures employed for dewaxing. Complete miscibility between the solvent and the oily constituents is necessary in order to secure a satisfactory separation of the wax crystals from the dewaxing solution.

In addition to having an unusually high solvent power for oil and a comparatively low solvent action for wax, the solvents of this invention have the desirable property of permitting an effective separation of wax and oil to take place at substantially room temperature. This unexpected property thus provides a dewaxing or deoiling procedure wherein the cooling step, heretofore essential with the use of conventional solvents, may be eliminated. Since refrigeration is a rather costly operation, the discovery of a solvent which will precipitate wax from oil at ambient temperature provides a separating medium of considerable value.

Representative of the fluorinated aromatic hydrocarbons which are contemplated for use as solvents in the present process for separating wax and oil are benzotrifluoride, xylene hexafluoride, fluorobenzene, fluorotoluene, fluoroxylene, fluoronaphthalene, and mixtures of two or more of the foregoing. The list of above mentioned compounds is not to be construed as limiting since other fluorinated aromatics boiling in the range of 150° F. to 450° F. may also be used. However,

under usual operating conditions, preference is accorded fluorinated aromatic hydrocarbons with fluorine present in a saturated aliphatic side chain attached to the aromatic nucleus. Benzo-trifluoride and mixtures thereof are particularly preferred since this compound is extremely effective in bringing about a separation of oil and wax at ambient temperature. A blend of benzo-trifluoride and xylene hexafluoride has, as will be shown hereinafter, been found to provide an excellent separation medium.

The solvents of the present invention may be employed in either deoiling operations, wherein a small amount of oil is removed from larger amounts of wax, or in dewaxing operations, wherein minor proportions of wax are removed from oil solutions. They are suitable for use in operations conducted over a wide range of temperature and pressure conditions. In carrying out the separation of wax and oil in accordance with the present invention, the solvent is added to the waxy oil and the mixture is heated to assure complete miscibility of all wax and oil fractions with the solvent. The mixture may then be cooled to a temperature between about -30° F.

and about 80° F. While the conventional dewaxing temperatures of from about -30° F. to about 30° F. may be used with the solvents of this invention, a particularly desirable feature of the fluorinated aromatic compounds employed herein is that they also permit an effective separation of the wax and oil at temperatures of from about 30° F. up to about 80° F. , thereby allowing the dewaxing or deoiling procedure to be effected at substantially room temperature. The exact temperature chosen will be dependent upon the character of the crystallized wax to be removed and the pour point desired in the dewaxed oil. The crystallized wax is removed either by filtration or by centrifuging, while the solvent is removed from the dewaxed oil fraction by distillation.

The amount of solvent employed may vary widely and depends upon the particular oily wax mixture being treated, the solvent employed, and the characteristics desired in the final product. In general, it is preferred to employ from one to four volumes of solvent per volume of oil being dewaxed.

Under certain conditions, the solvents of the present invention may be employed in conjunction with various other conventional solvents, such as ketones, benzol, petroleum, naphtha, lower boiling hydrocarbons, and the like.

It is also contemplated that the solvents of this invention may be used in the dewaxing of various types of mineral oil stocks or in the deoiling of different types of slack waxes and waxy

constituents. They may also be applied to the separation of wax-like bodies from other oil mixtures. Thus, they may be employed in the treatment of fatty oils and acids such as those derived from vegetable and animal sources.

The desirability of using the present class of dewaxing solvents may be seen from the following illustrative examples presented in tabular form, in which comparison is made between solvents of this invention and the conventionally employed blends of benzol and methylethyl ketone. The procedure followed in these examples was essentially as follows: A wax charge was brought into contact with the desired solvent, the ratio of solvent to petrolatum being about 4 to 1. The mixture was then heated to a temperature of 125° F. to insure thorough contact between the waxy charge and solvent. The mixture was then cooled to the desired filtration temperature, precipitating microcrystalline wax, and the wax was removed by filtration. The wax cake formed was washed once with solvent, removed, and the solvent separated from the cake by evaporation. The results obtained under varying conditions of temperature are set forth below:

Table 1

An examination of the above data clearly indicates that wax and oil mixtures can be effectively separated with the use of fluorinated aromatic hydrocarbon solvents at temperatures approximately 60° F. higher than with a conventional solvent mixture of benzol and methylethyl ketone. Particular attention is directed to the comparative results obtained in Examples 3 and 4. In Example 3, a blend of equal volumes of benzotrifluoride and xylene hexafluoride was employed at a temperature of 60° F. , while in Example 4, a blend of equal volumes of benzol and methylethyl ketone was employed at a temperature of 0° F. Approximately the same yields of microcrystalline waxes of equivalent characteristics were obtained in each of these examples. This indicates that the blend of fluorinated aromatic compounds can be used to give the same results at higher temperatures as are obtained with the benzol-methylethyl ketone blend at substantially lower temperatures. A further examination of the results obtained in Example 2 compared with those of Example 4 and the results obtained in Example 3 compared with those of Example 5 shows that the solvents of the present invention as compared with the conventional benzol-ketone blends give considerably greater yields of wax when the separation process is carried out under the same conditions of temperature.

It is apparent from the above results that the fluorinated aromatic hydrocarbon solvents of this

invention represent improved media for effecting the separation of wax and oil over a wide range of temperature and are particularly applicable in effecting said separation under ordinary temperature conditions, thereby eliminating the need for carrying out the separation process at low temperatures of the order of 0° F., which has heretofore been essential with the use of conventional solvent blends.

Obviously, many modifications and variations of the invention, as hereinbefore set forth, may be made without departing from the spirit and scope thereof and therefore only such limitations should be imposed as are indicated in the appended claims.

We claim:

1. A process for separating waxy constituents from an oil containing the same, which comprises admixing the oil with an oil solvent comprising an effective amount of xylene hexafluoride.

2. A process for separating waxy material from a mixture of oil and waxy material, which comprises mixing said mixture with a solvent comprising an effective amount of xylene hexafluoride, maintaining the mixture of feed and solvent at a temperature at which waxy constituents separate from the mixture in solid form while the oil remains substantially completely dissolved in the solvent and removing the solidified constituents therefrom.

3. A process for effecting the separation of a mixture of wax and oil, which includes the step of contacting said mixture with xylene hexafluoride.

4. A process for de-oiling a wax, which comprises contacting an oil-containing wax with an

oil solvent containing an effective amount of xylene hexafluoride.

5. A process for effecting the separation of a mixture of wax and oil, which comprises contacting said mixture with a solvent comprising an effective amount of xylene hexafluoride, heating the mixture of feed and solvent to a temperature sufficient to dissolve the wax, cooling the resulting mixture to a temperature between about 30° F. and about 80° F., during which time waxy constituents separate from the mixture in solid form while the oil remains substantially completely dissolved in the solvent and thereafter removing solidified constituents from the mixture.

10 6. A process for de-oiling a wax, which comprises contacting an oil-containing wax with an oil solvent consisting essentially of xylene hexafluoride, heating the mixture of feed and solvent to a temperature sufficient to dissolve the wax,

20 cooling the resulting mixture to a temperature between about 30° F. and about 80° F., during which time waxy constituents separate from the mixture in solid form while the oil remains dissolved in the solvent and thereafter removing solidified constituents from the mixture.
